DESIGN FOR A CURTAIN RUFFLE OR SIMILAR ARTICLE

Issie Poulin, St. Louis, Mo., assignor to St. Louis Curtain Company, St. Louis, Mo., a corporation of Missouri

Application January 15, 1934, Serial No. 50,410

Term of patent 3½ years

To all whom it may concern:

Be it known that I, Issie Poulin, a citizen of the United States, residing at the city of St. Louis, State of Missouri, have invented a certain new, original, and ornamental Design for a Curtain Ruffle or Similar Article, of which the following is a specification, reference being made to the accompanying drawing, forming a part thereof, in which,—

ruffle and indicating by broken lines the location of attachment of the ruffle to the body of the curtain; and Figure 2 is a transverse sectional view through the disclosure in Figure 1, taken on the line 2—2.

I claim—

The ornamental design for a curtain ruffle or similar article, substantially as shown and described.

ISSIE POULIN.
